UNITED STATES PATENT OFFICE

ARTHUR A. G. LAND, OF CHICAGO, ILLINOIS

CHAIN-LINK WIRE FABRIC

Application filed March 5, 1930. Serial No. 433,386.

My invention relates to chain link wire fabrics, namely fabrics composed of zigzag strands extending transversely of the fabric, with each strand presenting bights at each edge of the zigzag strand and with each two consecutive strands intertwined (or spirally twisted through each other) to interlock bights of these strands.

Each constituent strand for such a fabric usually has all legs of its zigzag formation disposed at the same angle of obliquity to the longitudinal axis of the strand, and the fabric when upright (as for example when used as a fence fabric) presents so called diamond meshes, each of which meshes has two horizontally opposite and two vertically opposite corners. This term "diamond mesh" is used in the wire trade as including thus disposed equal-sided quadrilateral meshes, regardless of the size of angle between any two consecutive mesh sides, and hence is here used in the same sense.

When such a diamond type of chain link wire fabric is tensioned longitudinally—as for example, when stretching it taut between two widely spaced fence posts—the strain tends to widen the mesh horizontally or longitudinally of the fabric and to contract the mesh transversely of the fabric, as for example by changing the mesh of Fig. 6 from the form shown in full lines to the shape indicated in dotted lines.

In a small sized fabric, such as a grille on a window, such a distortion of the mesh shape can be prevented by fastening the longitudinal edges of the fabric to spaced and rigid top and bottom bars. But such a complete framing of the fabric is usually prohibitive in cost with large fabrics, such as the long stretches of wire fabric between widely spaced fence posts.

Consequently, it has heretofore been customary to stiffen chain link wire fabrics against undue elongation by making them of much heavier wire than would otherwise be needed to resist the strains for which the fabric is designed, thereby undesirably increasing both the factory cost, the shipping expense and the cost of handling and erecting the fabric.

Furthermore, it also has been generally customary to construct such chain link wire fabrics with meshes having their heights equal to their widths, thereby requiring a considerably greater amount of wire (per given area of the fabric) than would be required with taller meshes for excluding objects of a given diameter, thereby still further increasing both the factory cost and the shipping expense.

My present invention aims to reduce the cost of chain link wire fabrics by providing mesh shapes which will more strongly resist distention longitudinally of the fabric than meshes of the usual diamond shape, and by disposing certain mesh sides so that a larger proportion of the fabric-tensioning strain will tend to elongate the wire (rather than to change the angles of the bends in the zigzag strand formations).

Furthermore, my invention aims to provide chain link wire fabrics in which novel mesh arrangements and mesh-side disposition will greatly enhance the longitudinal tensile strength of the fabric even when the greater portion of the fabric presents meshes of diamond or other shapes, or when most of the meshes are of shapes affording an increased object-excluding effect or are of decidedly ornamental appearance.

So also, my invention aims to accomplish these objects with the use of easily interwoven and cheaply manufactured strands, which strands can readily be varied in the shape of their zigzag formations to increase or decrease the resiliency of the fabric within a wide range.

Furthermore, my invention aims to provide easily manufactured and readily intertwined constituent strands for chain link wire fabrics in which novel but simple strand formations enhance the longitudinal resistance to tensioning strains; and aims to provide strand constructions which will readily permit the number and locations of these tension-enhancing strand formations to vary within a wide range and according to the tensioning strength and resiliency required in the fabric and according to the size and shape of meshes used.

Still further and also more detailed objects of my invention will appear from the following specification and from the accompanying drawings, in which drawings

5 Fig. 1 is an elevation of an end portion of a deltoid mesh wire fabric and of one of bars used for longitudinally tensioning the fabric.

10 Fig. 2 is an elevation of one of the counterpart strands of which the fabric portion of Fig. 1 is composed.

15 Fig. 3 is a plan view of the strand of Fig. 2.

Fig. 4 is an enlarged horizontal section taken along the line 4—4 of Fig. 1.

20 Fig. 5 is a section similar to Fig. 4, showing the use of strand bights extending through longer arcs so as to dispose the legs of the strand all in a common plane.

25 Fig. 6 is an elevation of a right-angled diamond mesh of a chain link wire fabric having the same ball-excluding effect and the same spread as the deltoid meshes in Fig. 1, with dotted lines showing the distortion of the diamond mesh by a longitudinal tensioning of the fabric.

30 Figs. 7, 8 and 9 are diagrammatic elevations of three shapes of diamond meshes, and Fig. 10 of a deltoid mesh, all having equal ball-excluding effects.

35 Figs. 11 and 12 are diagrammatic elevations of portions of my fabric including diamond shaped and deltoid meshes, the deltoid meshes presenting longitudinal rows of consecutively oblique tensioning legs.

40 Figs. 13 and 14 are diagrammatic elevations of portions of my fabrics composed partly of deltoid meshes and partly of diamond meshes formed for enhancing the longitudinal strength of the fabrics.

45 Fig. 15 is a diagrammatic elevation of a fabric including both diamond shaped and deltoid meshes, with part of the deltoid meshes formed to reduce the effective mesh openings.

50 Fig. 16 is an enlarged elevation of two of the deformed deltoid meshes of Fig. 15.

55 Figs. 17 to 19 are diagrammatic elevations of portions of my fabrics in which the main meshes include both deltoid and diamond shapes.

60 Fig. 20 is a diagram illustrating the tensioning effect of the less tall meshes in the fabric of Fig. 19.

65 Fig. 21 is a diagrammatic elevation of a portion of a fabric embodying my invention, showing a variety of mesh forms.

In accomplishing the purposes of my invention after the here presented manner, I employ these general principles pertaining to chain link wire fabrics:

70 With diamond shaped meshes formed by a wire of given character and size, the power required for increasing the spread of the mesh to a given degree varies with the size of the angles between the mesh sides and the direction of the spreading effort, and this power

decreases as the obliquity of the said angle decreases. For example, with diamond meshes formed for excluding all balls greater than the ball B shown in dotted lines in Figs. 7, 8 and 9, the power required (in the direction P) for laterally increasing the horizontal spread of each such mesh to the same linear extent will be greater for the square diamond mesh of Fig. 8 than for the vertically elongated mesh of Fig. 7, and will be still greater for the horizontally elongated mesh of Fig. 9.

75 In other words, the resistance of such meshes to a horizontal spreading effort (as when longitudinally tensioning a fence formed with such meshes) will be greatest when the height of the mesh is smallest in proportion to the lateral spread in the mesh.

80 In practice, this resistance to horizontal tensioning could be increased by a corresponding change in the shape of the mesh up to the point where the oblique angle O in Fig. 9 is about 170 degrees, at which approximate angle the mesh sides would stretch in length before permitting a further increase in the size of this oblique angle. As an example 85 of this difference in the resistance to a spreading of such meshes, I have found by experiment that with the same grade and size of wire, and the same length of sides in a mesh of the form of Fig. 9 (in which the oblique angle O is 150 degrees), it requires about twice as much power to increase the lateral spread of this mesh by a given length than with the mesh of Fig. 8 in which the oblique angle is 135 degrees.

90 In view of these considerations, it would theoretically be desirable to employ such diamond shaped meshes (for fences and the like) in shapes in which the horizontal spread of the mesh is far greater than the height of the mesh. However, such a shape is commercially objectionable because any considerable widening of the meshes increases the inside diameter of the roll into which the fabric can be rolled up for shipment; because wide meshes with sides at high obliquity to the horizontal afford too ready a foothold for any one wanting to climb the fence; and because the diminished height of the meshes means a proportional increase in the number of zigzag formations in each strand for a given height of the fabric, thereby increasing the cost of interweaving the strands. For these reasons, it is commercially undesirable to increase the longitudinal strength of such a fabric by forming the fabric entirely with meshes of greater width than their height.

95 However, my experiments in constructing chain link wire fabrics and testing their rigidity have also shown

100 (1) That such fabrics can readily be formed by interweaving counterpart strands in which each two consecutive strand legs are at different angles to the axis of the 105

strand, thereby increasing the resistance of the fabric to longitudinal tensioning; and

(2) That such fabrics can likewise be formed with vertical rows of meshes of equal spread, in each of which rows one or more meshes are of less height than the remaining meshes, and

(3) That such a shortening of one or more meshes in each vertical row (or row of meshes transverse of the fabric) effectively increases the longitudinal strength of the entire fabric.

Illustrative of the first of the two new types of fabrics prompted by my experiments, Fig. 1 shows a fragment of a chain link wire fabric formed by intertwining zig-zagged flattened spiral strands (all formed as shown in Fig. 2), each of which strands presents alined bights 15 at one lateral edge and alined bights 15 A at its other lateral edge, the alinement of each set of bights being on a line parallel to the axis A of the strand. Each such strand (as shown in Fig. 2) differs from the ordinary strand heretofore employed for this class of fabrics in that the two legs 6 and 7 of each of the repeated zigzag formations are of unequal lengths, and are disposed at different angles of obliquity (18, 19) to the horizontal.

Owing to these differences, one of each two consecutive strand legs (6) can readily be disposed at the increased angle of obliquity 18 to the horizontal, which affords a decided increase in the resistance of the resulting meshes to a horizontal tensioning strain (or strain longitudinal of the fabric), while the other stand leg 7 (which forms a side of the same mesh with the adjacent leg 6) is disposed at the decreased angle of obliquity 19 to the horizontal which affords a greater height of mesh and reduces the cost of intertwining the strands.

When such a fabric is tensioned longitudinally, as in stretching a fence fabric secured at one end to a tensioning bar 11 which extends through the bights at that end of the fabric (Fig. 1), each of the end bights 15 A forms a fulcrum about which the horizontal pull along the lines P and P' tends to rock the legs 6 and 7 respectively. However, the component 9 of the pull P is much shorter than the component 10 of the equal pull P', so that a much larger proportion of the pull P tends to elongate the leg 6 on which it is exerted than of the pull P' on the leg 7. The shorter the mesh legs 6, or the shorter the distance 9, the greater will be the resistance of the shorter mesh sides 6 to a longitudinal tensioning.

Consequently, the same effort which will bend the leg 7 to move its free (lower) end a given distance horizontally will not suffice for a similar horizontal movement of the free (upper) end of the leg 6. The same holds true in the other meshes of the fabric, par-

ticularly since the rows of consecutive legs 6 A diverge by much greater angles than the companion legs 7 A. Moreover, this increased tensioning effect of the shorter mesh legs is also transmitted obliquely of the fabric 70 (as for example along the mesh sides marked 16) to other short legs, so that the entire fabric is strengthened in this manner.

This result has also been confirmed by experimental tests on chain link fabrics made 75 of the same size and grade of wire, and of the same area. For example, a test of the fabric of Fig. 1 in comparison with one having the meshes of Fig. 6 (and excluding the same maximum size of balls B) showed that it 80 required approximately a fifty percent greater pull to elongate the deltoid mesh fabric of Fig. 1 to the same extent as a fabric having the (right-angled) diamond meshes of Fig. 6. Consequently, the substitution of 85 my deltoid meshes for the diamond meshes in a fabric with the same ball-excluding effectiveness permits the securing of the same longitudinal tensile strength with the use of a much smaller size of wire, which means a 90 decided saving in the cost of the fabric.

These tests have also shown that with the deltoid mesh of the shape of Fig. 10 and of a size excluding the same size of balls as the meshes of Figs. 7 to 9 inclusive, the deltoid 95 mesh of Fig. 10 is approximately equal in longitudinal resistance to tension to the mesh of Fig. 9, so that by the use of such deltoid meshes (with their axes of symmetry 20 transverse of the fabric) I can secure all the 100 advantages of the mesh of Fig. 9 without the disadvantage of the latter in providing widened footholds when the fabric is used as a fence.

However, such tension-enhancing forms of 105 meshes need not be employed for the entire area of a fabric, as they can readily be combined both with meshes shaped for a further increase of the longitudinal strength of the fabric, or with meshes of less resistance to tensioning (longitudinally of the fabric) than the deltoid meshes. For example, a deltoid fabric can be strengthened still further by adding a longitudinal edge row of 110 diamond meshes S of the same spread, but of 115 less height, than the deltoid meshes D as shown in Fig. 13. Or, such longitudinal rows of diamond meshes S can be included both at the longitudinal edges and in transversely spaced rows extending lengthwise of 120 the fabric, as shown in Fig. 14, to obtain a greater longitudinal strengthening of the fabric than that obtained in the fabric of Fig. 13.

By varying the number of rows of deltoid 125 meshes thus interposed between each row of the diamond meshes S I can correspondingly vary the degree to which the fabric can be tensioned longitudinally when made of a given size of wire and with a given shape and 130

size of each type of the meshes. This enhanced tensioning effect will obviously be greatest when the longitudinal rows of deltoid meshes alternate with the rows of diamond meshes, when the diamond meshes are of less spread transversely of the fabric (or vertically in an upright fabric) than longitudinally of the fabric. Consequently, I can secure an enhanced longitudinal rigidity even with deltoid fence meshes of great height in proportion to their width by interposing such a longitudinal row of diamond meshes between every two longitudinal rows of the deltoid meshes, as in Fig. 17.

The underlying principle of my invention—namely that of providing longitudinally extending zigzag rows of mesh sides in which the successive mesh sides of each zigzag row diverge at greater angles than the mesh sides in other rows longitudinal of the fabric—may also be employed in fabrics in which widely varying proportions of the meshes are of other than deltoid forms. For example, Figs. 11 and 12 diagrammatically show portions of fabrics, in which most of the meshes 13 are of a vertically elongated diamond shape, while other meshes D are of deltoid shape and afford the highly obtuse angled and longitudinally extending rows of mesh sides T for increasing the longitudinal strength of the fabric.

All heretofore proposed chain link wire fabrics have been formed of strands in which the distances between consecutive bights at each edge of the strand are equal, so that the meshes formed by each two consecutive strands are all of the same height and shape. However, I have discovered that zigzag strands can also be consecutively intertwined into a fabric when the zigzag formations in each strand are not all counterparts of one another and when the consecutive spacings of the bights at one or both edges of the single strand are not all equal. When such strands are assembled in a fabric, consecutive strands form meshes of different heights transversely of the fabric or longitudinally of the strands.

For example, in the strands of the fabric as shown in Fig. 11, which are so formed that the bights alternate at opposite edges of the strands, the left-hand strand is so formed that the distances between the consecutive bights at the left-hand edge of the strand are equal in a portion of the strand as shown by the bights spacings H, and the distance J between the bights 24 and 25 is much less than the distances H. The spacings between consecutive bights on the right-hand edge of this strand also are respectively equal and unequal in different portions of the strand.

Also, all of the legs (or mesh sides) of each strand of Fig. 11 extend oblique to the axis A of the strand. These legs are of different lengths, portions of each strand including

consecutive legs of equal length and other portions including consecutive legs of different lengths.

For example, in the right-hand strand of the fabric of Fig. 11 the consecutive legs T 70 and 21 are of different lengths and cross the axis A of the strand at different angles of obliquity and form two consecutive sides of the deltoid mesh D; the consecutive legs 22 are of equal length and are longer than the short legs T and also cross the axis A of the strand at oblique angles and form two consecutive sides of the four-sided mesh 13, which is of greater height transversely of the fabric than the deltoid shaped mesh D. 80

When strands so formed are assembled in a fabric, each two strands form a row of meshes longitudinally of the strands or transversely of the fabric, which meshes have all of their mesh sides extending oblique to the edge line 85 Z of the fabric. The meshes D and 13 are of uniform width longitudinally of the fabric, but the meshes 13 are much taller than the meshes D so that the meshes are of different spreads transversely of the fabric. 90

However, in the completed fabric the meshes of each longitudinal row are all of the same shape, either all deltoid shaped meshes D or are all four-sided or parallelogram shape meshes 13. The top mesh section of the fabric of Fig. 11 shows two longitudinal rows of deltoid shaped meshes D between which are three longitudinal rows of parallelogram shaped meshes 13, and the two longitudinal rows of deltoid shaped meshes 100 D in the center are interposed between longitudinal rows of parallelogram shaped meshes 13. 100

Also the mesh sides T form contiguous zigzag lines extending longitudinally of the fabric and are of different angularity than the contiguous zigzag lines formed by the mesh sides 21. These two contiguous zigzag lines border meshes D which are all of deltoid shape. 105

However, wherever two contiguous longitudinal zigzag lines are both constituted by mesh sides 22, as in the major portion of Fig. 11, the uniform angularity at which the mesh sides consecutively diverge from each other causes these contiguous zigzag lines to border meshes 13 of parallelogram shape. 110

The fabric of Fig. 12 also has the strands so formed that the spacings between consecutive bights at one edge of the strand are unequal, so that the distance J' between the bights 26 and 27 is less than the distance H' between the bights 27 and 28. 120

In Fig. 15 the left-hand strand has the distances between consecutive bights H² and J² at the left-hand edge of this strand unequal, while the distances K between consecutive bights on the right-hand edge of the strand are all equal. 125

When such counterpart strands are assem- 130

bled to form a fabric, the bights at each edge of a strand are interlocked with the similarly spaced bights in one edge of the next strand, so that each two strands form a row of meshes extending transversely of the fabric, but each two such consecutive rows presents different mesh formations. Thus, the left-hand transverse row of meshes (shown vertically in Fig. 15) is formed by strands in which the intertwined bights are equally spaced, so that the meshes of that row are all of deltoid shape and of equal height, although some meshes R may be deformed from their fundamental deltoid shape (which fundamental shape is shown in dotted lines) so as to differ in appearance from the true deltoid shaped meshes D.

In the next such row, the heretofore recited departure from a uniform consecutive spacing of the bights at the strand edges which have their bights intertwined to form the meshes of that row causes these two strands to form the sides of meshes which are all of parallelogram shape, but of two alternately different heights, such as the tall meshes M and the shorter meshes S. And where the strand portions are such as to modify the deltoid shape of meshes in the adjacent row, the corresponding tall mesh M' is likewise deformed from its fundamental shape which is a parallelogram.

Consequently, by thus using zigzag strands in each of which the bight spacings at the two edges of the strand are respectively equal and unequal, I can produce decidedly novel and ornamental effects, in addition to profiting by the enhanced resistance to a longitudinal tensioning of the fabric which is afforded by the interconnected strand legs which border the short parallelogram-shaped meshes S.

Moreover, by varying the spacings of the bights at either one or both edges of counterpart zigzag strands, I can correspondingly vary both the appearance of the resulting fabric and the extent to which the resistance of the fabric to longitudinal tensioning is enhanced by the presentation of the more oblique angled longitudinal zigzag lines T formed by the strand legs which border the shorter parallelogram-shaped meshes.

For example, by arranging the strand-edge bight spacings as in Fig. 17, I can produce a fabric presenting spaced longitudinal rows of parallelogram-shaped meshes (of less height than width), and interposed single rows of relatively taller deltoid meshes, in each of which interposed rows the deltoids are alternately upright and inverted.

So also, by other variations of the said bight spacings, I can produce fabrics in which most of the taller meshes are of a parallelogram shape and with varying numbers of rows of the taller meshes between consecutive rows of the relatively short tension-

resistance-enhancing meshes of parallelogram shape S. With such variations, the meshes adjacent to the said shorter meshes S may be partly of deltoid shape, as in Figs. 18 and 19.

To enhance this tensioning effect, I may include vertically elongated diamond-shaped meshes S in a fabric having the major portion of its area formed of deltoid meshes D. This can be done with a single longitudinal row of such diamond-shaped tensioning meshes, as in Fig. 13, or with more numerous rows as in Fig. 14, in either of which fabrics each such row of diamond-shaped meshes presents two rows of obtuse angled tensioning legs.

Fig. 15 diagrammatically shows a fragment of a fabric including relatively tall diamond meshes M, deltoid meshes D, and vertically contracted diamond meshes S. With such combinations of deltoid meshes and diamond meshes, the longitudinal rigidity of the fabric can be further enhanced by increasing the number of deltoid meshes (and hence of the rows of tensioning legs T) in proportion to the number of diamond meshes which are elongated transversely of the fabric. This can be done after the manner of Fig. 11 with single rows of tensioning legs T; or as in Fig. 17 with interposed diamond meshes affording double rows of such tensioning legs, thereby doubling the resistance to tensioning in this fabric and thereby permitting lighter wire to be used for the fabrics than would be permissible if all of the meshes of the fabric corresponded in shape to the diamond form of meshes 13 shown in Fig. 11.

The reason for this increase in longitudinal strength by the inclusion of diamond meshes which are less tall (transversely of the fabric) than other meshes will be obvious from Fig. 20, which has dotted lines showing both a square diamond mesh and a vertically contracted diamond mesh as distended longitudinally of the fabric to the same extent. To do this, the angle W would have to be decreased to a much greater degree than the angle Y, which would require much greater power.

Fig. 15 also includes meshes R which are fundamentally of a deltoid form (as shown in dotted lines) but which have their longer legs bowed out of the general direction in which these legs extend and in the general plane of the fabric. This deforming of the deltoid meshes greatly reduces the maximum size of ball which will pass through each mesh, as shown in Fig. 16, in comparison with the pure deltoid shape, as shown by comparing the ball B with the ball B', but by leaving the shorter legs straight I will secure the tension-increasing effect.

Owing to the high effectiveness of such highly obtusely zigzagged rows of mesh sides, my invention also makes it feasible to use

light wires for chain link wire fabrics having meshes of great height in proportion to their widths, and likewise permits such meshes to have some of their sides deformed (out of the general direction in which those sides extend, but approximately in the general plane of the fabric), to provide an endless variety of ornamental fabrics, as shown for example by the varied forms of meshes in Fig. 21. In this figure, each mesh is fundamentally of a deltoid shape, as shown by the dotted lines 15 for meshes at the upper left hand corner of the figure, but the deforming of two mesh sides out of the shape shown in dotted lines reduces the effective mesh opening, after the manner more fully disclosed in my Patent #1,816,361, issued July 28, 1931 on a wire fence or grille. Hence my invention also provides effective means for increasing the strength of the mesh-opening-reducing fabrics disclosed in my said co-pending application.

As the result of the heretofore recited differences in the lengths of some of the consecutive legs of each strand, the spacing of at least one bight in the strand from the two adjacent bights at the same edge of the strand is unequal. For example, in the zigzag strand at the right-hand edge of Fig. 12, the bight at the right-hand end of each leg T is unequally spaced from the next higher and the next lower bight at the same edge of the strand. Consequently, each bight which is thus spaced unequally from the two bights between which it is interposed at the same edge of the strand is at the common corner of two meshes of a mesh row transversely the fabric (or upright in Fig. 12), which two meshes D and 13 are both different appearance and of unequal spread longitudinally of the said row—as for example, the two meshes respectively above and below the juncture of one of the pairs of legs jointly designated as T in that figure.

Moreover, it will be noted that in the longitudinal rows of mesh legs which afford the increased tensioning resistance in my fabric, the consecutive mesh legs in each such row extend at obtuse angles to each other. Consequently, each two consecutive legs can still change their relative direction momentarily under severe strain, such as the resiliency of the wire will withstand; and not a single row of mesh legs has the mesh legs of that row extending at right angles to the parallel axes of the strands. When mesh sides do extend at right angles to the axes of the intertwined zigzag strands—as has heretofore been proposed—such mesh sides portions aline longitudinally of the fabric to form rigid chains, thereby preventing a change in the shape of the meshes either by a longitudinal tensioning of the fabric or by the impact of objects against the fabric transversely of its general plane.

By disposing all strand legs or mesh sides of the fabric (including those at the edges of the fabric) oblique to the longitudinal edge lines of the fabric I overcome the rigidity which the fabric would have if part of these strand legs or mesh sides extended parallel to the said longitudinal edge line. As the result, my fabric still has the resiliency and extensibility which is needed in practice to avoid the crystallizing and weakening which impacts will effect on longitudinally alined and rigidly tensioned strand legs; while still disposing a portion of these strand legs so that they will offer a greater resistance to a longitudinal tensioning of the fabric than other strand legs; this increased resistance to longitudinal tensioning being desirably along at least one longitudinal edge of the fabric and in as many other parts of the fabric (spaced transversely of the fabric from one another), as may be required according to the directions of the strand legs interposed between the fabric portions affording this increased resistance to longitudinal tension and according to the degree of resiliency desired in the fabric for its intended use. For this reason, my here presented fabric is more desirable than fabrics in which the tension-enhancing legs are in substantially straight rows (as disclosed in my co-pending application No. 428,889) for purposes where considerable resiliency is desired—as for example, for use in guard fences along automobile highways.

However, while I have described my invention in connection with its use as a fabric for fences, I do not wish to be limited in this respect. Nor do I wish to be limited to the details of the construction and arrangement here disclosed, since many changes might be made without departing either from the spirit of my invention or from the appended claims. In this connection, it is to be understood that I am using the terms "strand legs" and "mesh sides" in the appended claims in the broad meanings in which these legs or sides may be either straight or provided with deformations; that I am likewise using the terms "parallelogram" and "deltoid" in the broad sense in which these terms indicate figures in which the general direction of the sides extends correspondingly; and that the term "diamond" in the claims broadly includes equal-sided parallelograms regardless of the relative angular disposition of the sides thereof.

I claim as my invention:

1. A constituent strand for a chain link type of wire fabric comprising a wire bent to a flattened spiral zigzag formation of uniform width and presenting legs of two different lengths all disposed oblique to the general axis of the strand, the strand including a portion in which consecutive legs are of the

same length and a portion in which consecutive legs are of different lengths.

2. A constituent strand for a chain link wire fabric, as per claim 1, in which legs of the longer length are provided intermediate of their ends with bends lying in planes parallel to the general plane of the strand, the shorter legs all being substantially straight.

3. A chain link wire fabric comprising consecutively intertwined strands extending transversely of the fabric, each strand being of zigzag formation and presenting bights at each edge of the strand, each two consecutive bights being connected by a strand leg forming a mesh side in the assembled fabric; each strand including consecutive legs disposed at oblique angles of different angularity to the axis of the strand, whereby the meshes bordered by two such successive and differently oblique legs of two consecutive strands are of a fundamentally deltoid form; each strand also including consecutive legs disposed at equal angles to the axis of the strand, whereby the meshes bordered by legs of the last named disposition in two consecutive strands are of the general form of parallelograms.

4. A strand for a chain link type of wire fabric comprising a wire bent to a zigzag formation of uniform width and presenting bights alternately at opposite edges of the strand with each two bights connected by a strand leg, the general direction of the strand legs being oblique to the general axis of the strand, the strand including a portion intermediate of the end legs of the strand in which the distances between consecutive bights at one edge of the strand are unequal.

5. A wire fabric comprising zigzag strands extending transversely of the fabric and consecutively intertwined so that each two consecutive strands border a row of meshes extending transversely of the fabric, all of the mesh sides of each such mesh having their general direction oblique to the longitudinal edges of the fabric; the zigzag formation of the strands being such that in certain of the said mesh rows a mesh is of less height transversely of the fabric than the meshes between which that mesh is interposed.

6. A wire fabric comprising consecutively intertwined zigzag strands each presenting consecutively diverging legs oblique to the axis of the strand; each strand including strand portions in which consecutive legs are of relatively different lengths, whereby these portions of two adjacent strands form meshes of substantially deltoid shape; each strand also including at least one portion in which two consecutive legs are of equal length, so that the last named portions of two consecutive strands form meshes of parallelogram shape.

7. A wire fabric comprising consecutively intertwined zigzag strands extending transversely of the fabric and each presenting legs

all oblique to its axis, with some of the legs (including each end leg of the strand and at least one leg spaced from both end legs) disposed at greater obliquity to the axis of the zigzag strand than other legs; whereby the corresponding legs in the several strands which are at the said greater obliquity form zigzag lines in the fabric extending longitudinally of the fabric, and whereby the less oblique corresponding legs in the several strands form similarly extending zigzag lines of less angularity than the aforesaid zigzag lines.

8. A wire fabric comprising consecutively intertwined zigzag strands each of uniform width and presenting consecutively diverging legs oblique to the axis of the strand; each strand including strand portions intermediate of its end legs, in which portions consecutive legs are of relatively different lengths, whereby these portions of two adjacent strands form meshes of substantially deltoid shape; each strand also including intermediate of its end legs at least one portion in which two consecutive legs are of a different length than one of the first named consecutive legs, whereby the last named portions of two consecutive strands form four-sided meshes of different appearance from the said deltoid-shaped meshes.

9. A constituent strand for a chain link type of wire fabric comprising a wire bent to a flattened spiral zigzag formation of uniform spread and presenting consecutively diverging strand legs all oblique to the axis of the zigzag strand; the greater portion of the length of each strand being composed of legs extending at less obliquity to the said axis than the legs comprising the remaining portions of the strand, the latter legs including at least one leg spaced from both end legs of the strand, and at least one portion of the strand being composed of consecutive legs of equal obliquity.

10. A wire fabric comprising zigzag strands extending transversely of the fabric and consecutively intertwined so that each two consecutive strands border a row of meshes extending transversely of the fabric, all of the sides of each such mesh having their general directions oblique to the longitudinal edges of the fabric; the zigzag formation causing each strand to present an aligned row of bights at each edge, and being such that in each strand a bight at one edge thereof is spaced by unequal distances from the two bights at the same strand edge between which it is interposed, whereby the first named bight is at a corner of two adjacent meshes of one of the said rows, which adjacent meshes are of unequal spread longitudinally of that row.

Signed at Chicago, Illinois, March 1st, 1930.
